RING BINDER

Irwin E. Price, Worcester, Mass., assignor to Price Brothers Plastics Corporation, Worcester, Mass., a corporation of Massachusetts

Filed Dec. 28, 1961, Ser. No. 68,108

Term of patent 14 years

(Cl. D6—2)

FIG. 1 is a perspective view of a ring binder embodying my new design,

FIG. 2 is a front elevational view thereof,

FIG. 3 is a left hand end view thereof,

FIG. 4 is a rear elevational view thereof,

FIG. 5 is a top plan view; and

FIG. 6 is a sectional view taken on the line 6—6 of FIG. 2.

The essential features of the design reside in the portions shown in solid lines.

I claim:

The ornamental design for a ring binder, as shown and described.
